Primary Examiner — Jennifer Rivard(74) *Attorney, Agent, or Firm* — Cooper & Dunham LLP(57) **CLAIM**

The ornamental design for a foot callus remover, as shown and described.

DESCRIPTION

FIG. 1 is a top, front and right side perspective view of a foot callus remover showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom, rear and right side perspective view thereof.

The broken lines in the drawings illustrate portions of the foot callus remover which form no part of the claimed design.

1 Claim, 8 Drawing Sheets---
